UNITED STATES PATENT OFFICE.

KENNETH J. TOBIN AND WILLIAM W. DARROW, OF CHICAGO, ILLINOIS, ASSIGNORS TO CAMEL COMPANY, OF CHICAGO, ILLINOIS, A CORPORATION OF ILLINOIS.

METAL-DOOR CONSTRUCTION.

Application filed December 15, 1924. Serial No. 755,823.

This invention relates to a metal car door and suspension therefor.

The difficulty heretofore encountered in the attempts to use metal car doors existed in the fact that they did not combine the proper strength and lightness of weight, and could not be economically constructed. On account of the strain arising from the pressure of the lading within the car and the severe usage to which such doors are put, it is necessary that they be made exceptionally strong. The excessive weight of the doors heretofore constructed and their lack of proper weatherproofing features has rendered the same impractical.

It is an object of this invention to provide a practical car door that combines the requisite rigidity, durability and lightness of weight, that can be economically manufactured, and that is not likely to become distorted so that it will cause a binding when open or closed.

It is a further object of this invention to provide a metal door having a smooth or plain inner surface to reduce the possibility of the lading within the car that may come in contact with the door from interfering with or obstructing its operation.

It is a further object of this invention to provide an efficient weatherproofing construction in connection with such a door that will draw and maintain the same in close relation with the car.

With these and other objects in view which will become more apparent in the following description and disclosures, this invention comprises the novel structure and combinations hereinafter described and more particularly pointed out and defined in the appended claims.

In the accompanying drawings which illustrate a preferred embodiment of this invention and in which similar reference numerals refer to similar features in the different views.

Figure 1 is a fragmentary side elevational view of a freight car illustrating a sliding door construction involving this invention.

Figure 2 is an enlarged top plan view of the door.

Figure 3 is an enlarged broken horizontal sectional view upon the line III—III of Figure 1.

Figure 4 is an enlarged fragmentary ele-

vational view of a part of the door illustrating the anti-friction rolls and with parts broken away to show the door panel.

Figure 5 is an enlarged side elevational view of the door with parts broken away.

Figure 6 is an enlarged broken sectional view upon the line VI—VI of Figure 1.

Figure 7 is a fragmentary perspective view illustrating certain features.

Figure 8 is a slight modification in section of a certain part of the door construction illustrating weatherproofing features.

Figure 9 is a fragmentary plan view of a slightly modified form of door construction.

Referring now to the drawing which illustrates one embodiment of this invention, it will be observed that the metal car door comprises a frame consisting of a lower T-bar 1 having outwardly projecting indenture portions 2 on its depending flange for engagement with the usual guides 3 on the lower side of the car; a front angle 4 which has a rearwardly projecting and outwardly inclined flange 4^a which wedges against the rearwardly extending and outwardly inclined flange 5^a of a vertical angle bar 5 secured to the front post for drawing the door inwardly; a vertical rear angle 6 having a forwardly extending flange 6^a which terminates in a rearwardly extending terminal 6^b which is adapted to slide against the inwardly inclined flange 7^a of a channel 7 secured to the door post and facing rearward; the inclined flange 6^a contacting the outer flange 7^b of the channel which has an enlargement for this purpose; and an upper Z-bar 8. These members are suitably secured together and T-bars 9 extend in spaced relation between the angles 5 and 6 for supporting adjacent margins of panel sections as will later appear.

It will be noted with reference to Fig. 3 that when the door is in closed position, the front end of the front angle 4 is spaced a distance from the attaching flange of the cooperating angle bar 5 and does not strike the same. This structure will always insure a proper wedging action even though there should be a wearing or distortion of parts.

There will also consequently be a certain amount of resiliency with respect to the wedging parts.

The door panel consists of a plurality of sections 10. Each section consists of an inner flat ply and an outer outwardly cor-

ruggeded ply whereby a strong but nevertheless light structure is provided and as the inner ply is flat, the movements of the door are not likely to be impeded or obstructed 5 by lading coming in contact therewith as would happen if the lading could come in contact with the corrugations. While these panel sections may be constructed in various ways in the present embodiment of this invention, suitable sheets of metal of proper length are corrugated between two intermediate points which are preferably spaced equal distances from the ends of the sheet. In the present instance, the intermediate 10 corrugated portion of each sheet, which constitutes the outer ply, is substantially equal to an uncorrugated end portion, thereby constituting substantially the intermediate third of the sheet after corrugation. The major portion of each uncorrugated end portion is then folded over and superposed 15 upon the back of the sheet as clearly shown in Figure 3. The ends of the superposed portion are brought into overlapping relation and riveted to the corrugated portion. These uncorrugated superposed portions form the inner ply of the panel sections and greatly strengthen the same. It will be noted that the flat end portions are folded 20 at points spaced from the end corrugations to provide suitable flat portions for attaching the panel sections to the door frame.

In the present instance the door panel consists of three such sections; the lower 25 panel section fits in the space defined by the T-bar 1 and the adjacent T-bar 9, and its margins are riveted to the flanges of these T-bars and its ends are respectively riveted to the front and rear angles 4 and 6. The next panel section 10 is secured in a similar 30 way between the T-bars 9, and the upper panel section 10 is secured between the upper T-bar 9 and the Z-bar 8 by being riveted to the flanges thereof and to the flanges of the front and rear edge angles. The corrugations of these panel sections fit 35 between the outstanding flanges of the T-bars and the ends thereof abut these outstanding flanges, except the upper end of the upper panel section which abuts the web of the Z-bar 8. It will obviously be 40 appreciated that the ends of these corrugations have a bracing effect against the flanges of the T-bars and as the securing 45 rivets of the panel sections extend through a double thickness of metal, there is little liability of the panel sections tearing at the rivet holes.

A modified form of T-bar 9^a (Fig. 8) 50 having a depending lip 9^b upon the margin of its outstanding flange may be used that overlaps the lower corrugation and more effectively sheds the rain and weather elements. Where lips 9^b are not provided on 55 the T bars, the inner ply may be crimped

over the top edge of the outer ply as indicated at 16 in Figure 7, to prevent the rain and weather from entering.

In the structure shown in Figures 1 to 8 the corrugations of the door panel extend vertically and the corrugations of the sections are in alinement whereby the rain may be quickly carried off. However, in some cases it might be desirable to have the corrugations extend horizontally and in Figure 9 we have illustrated such a structure, the adjacent panel sections 10^a being of double thickness as before described and being riveted to the T-bars 9, the horizontal corrugations extending parallel to the T-bars. 75

A novel form of supporting means has been provided for pivotally supporting the door in balanced position and which allows the same to be tilted in the plane thereof to assist in opening and closing the same. 85 This supporting means consists of a single hanger 11 secured to the upper central part of the door and projecting thereabove, and overhanging a supporting track 12 which consists of a Z-bar having a depending 90 flange overlapping the upstanding flange of the Z-bar 8 in combination with a roller 13 journaled in this hanger and adapted for traveling on the track 12. This roller and its hanger are so positioned that the door 95 will be supported in balanced position.

Adjacent each end of the upper Z-bar 8 of the door, there is supported an anti-friction element 14 which consists of a roller having its spindle supported in the upstanding flange of the Z-bar 8 and in the upstanding flange of a lug 15 secured to the web of the said Z-bar. In the balanced position of the door these anti-friction rolls are spaced a short distance below the track 105 12 as shown in Figure 6. The roll 13 which is the sole means for supporting the door acts as a pivot so that the door can pivot thereon or be tilted in the plane thereof in accordance with the clearance between the anti-friction rollers 14 and the track; these rolls 14 hence limit the tilting movement of the door and confine the same within desirable limits and absorb the friction that would arise if the door contacted 110 the track.

It will be appreciated that on account of the single pivotal support for the door there is little likelihood of a binding effect arising between the car and door due to the distortion of the car during travel. Further, as the door can be readily tilted on its pivotal roller support to a limited extent, it can be readily loosened if there should be a slight binding between it and the car. It 120 should also be observed that such tilting of the door in its plane will assist in the operation of the door from any position. However, the subject matter of this hanger and manner of supporting the door is not 125

claimed in this application but is made the subject matter of a co-pending application.

From the foregoing it will be apparent that a light but nevertheless strong and durable metal door has been provided that is held in its closed position by efficient weather proofing means and that is pivotally supported for limited tilting movement for overcoming the usual binding effect.

10 We are aware that numerous details of construction may be varied through a wide range without departing from the principles of this invention and we therefore do not purpose limiting the patent granted 15 otherwise than necessitated by the prior art.

We claim as our invention:

1. In a metal car door, a frame comprising a lower T-bar having an outstanding 20 flange, and a plurality of flanged members in spaced relation to said T-bar, each of said members having an outwardly directed flange, in combination with corrugated panel sections supported by said bar and members. 25 with the corrugations thereof extending between said flanges.

2. In a car door, a frame comprising a pair of outwardly flanged members in spaced relation, a panel section between said 30 members, said section comprising a flat inner ply and an outer corrugated ply, the corrugations of said outer ply extending lengthwise between said flanges.

3. In a freight car having a doorway, a 35 sliding door mounted in said doorway, a rear edge angle on said door having an inwardly and forwardly inclined flange with a rearwardly inclined terminal and a cooperating channel member at the rear end of said doorway adapted for contacting relation with said inclined flange and terminal.

4. In a metal car door, a frame comprising an upper Z-bar and a lower T-bar connected by side members having deformed 45 flanged portions for weather proofing purposes, T-bars in spaced relation on said side members, and panel sections secured to said frame.

5. In a metal car door, a frame comprising an upper flanged member and a lower flanged member, side angle bars with deformed flanges connecting said members, and two-ply panel sections secured to said angle bars and members.

6. In a metal car door, a frame comprising a pair of vertically spaced members having outwardly directed flanges, a panel section having outwardly extending corrugations secured between said members with the ends of the corrugations abutting said 60 flanges, said outwardly extending flanges having beads depending over said corrugations.

7. In a car door structure, a pair of opposed frame members having outwardly directed flanges a panel section between said members, said section comprising an outer corrugated ply having flat end portions folded under said corrugated ply, the ends of the corrugations of said panel abutting 70 said flanges.

8. In a metal car door structure, a panel section comprising an outer corrugated ply having integral flat portions folded under the outer ply for reinforcing the same, and 75 means connecting the folded portions to the outer ply.

9. In a freight car having a door-way, a sliding door mounted in said door-way, a rear edge angle on said door having an 80 inwardly-directed and deformed flange, and a cooperating channel member at the rear end of the doorway, an intermediate point of said deformed flange contacting one flange of said channel and the inner portion thereof contacting the other flange of said channel when the door is in closed position.

10. In a house car having a doorway with a jamb at one end of said doorway, an angle bar having a flange attached to said jamb and a rearwardly extending and outwardly sloping flange, the juncture of said flanges being substantially at right angles, 90 a door having a front edge angle member, one flange of which is attached to the door and the other flange of which is rearwardly bent and outwardly inclined for engaging under said sloping flange, the construction 95 being such that the front edge of said angle member is normally spaced from the attaching flange of said angle bar when the door is in closed position to allow for a yield upon impact.

In testimony whereof we have hereunto 105 subscribed our names.

KENNETH J. TOBIN.
